UNITED STATES PATENT OFFICE.

ABRAHAM BURNSTINE, OF WASHINGTON, DISTRICT OF COLUMBIA.

SECOND-HAND-SETTING MECHANISM FOR WATCHES.

1,421,668.

Specification of Letters Patent.

Patented July 4, 1922.

Original application filed March 31, 1922, Serial No. 548,324. Divided and this application filed May 25, 1922. Serial No. 563,476.

To all whom it may concern:

Be it known that ABRAHAM BURNSTINE, a citizen of the United States, residing at Washington, in the District of Columbia, has invented certain new and useful Improvements in Second-Hand-Setting Mechanism for Watches, of which the following is a specification.

This invention relates to a second-hand setting mechanism for watches, and is a divisional application of my original application filed March 31, 1922, Serial Number 548,324, also for second-hand setting mechanism for watches.

15 As stated above, my invention relates to second-hand setting mechanism for watches, designed with the object and purpose of providing a means whereby the second-hand may be caused to be started, for instance, 20 from the 60 mark on the second-hand dial at the instant the minute hand rests over the full-minute mark on the watch dial so that the second-hand will correctly indicate at all times the number of seconds the minute 25 has traveled intermediate any two minute marks on the watch dial. In other words, this invention is designed for the purpose of producing a construction whereby the second and minute hands may be caused to 30 operate in synchronism.

I produce this result by a simple watch-stem controlled mechanism which will arrest the movement of the second-hand when it has completed its cycle over the dial and 35 rests over the 60 mark thereon; the arresting movement of the second-hand also acting to stop the action of the entire watch movement, after which time, should the minute hand be not properly positioned with respect to the second-hand, it may be set directly over its full minute mark, and the 40 second-hand operating mechanism released whereupon the full watch movement will be permitted to be brought into action, at 45 which time the minute and second-hands will start from their respective full minute positions.

An attachment for this purpose is particularly adapted for railroad watches 50 where accuracy in time, both with respect to the minute and second is an element of exceedingly great importance, although the field for its usefulness is not limited to its use in this particular manner, being equally

as well adapted for any watch carrying a 55 second-hand.

While I am aware that this broad idea has been attempted to be placed to use with a varying degree of success, I believe I am the first to design a construction for the 60 purpose specified which is so simple in its arrangement and so effective in its operation, and which resides only in the addition of a few mechanical elements to a watch of ordinary type.

65 In the construction with which I am familiar, a decided re-arrangement of parts and complex additional elements were necessary to arrive at the object for which my invention has been designed.

70 In the accompanying drawing which illustrates a preferred embodiment of my invention,

Figure 1 is an illustration of the adaptation of my invention to a clutch mechanism 75 in a modern watch.

Figure 2 is a perspective view of the spring member used in my device.

Figure 3 is a slightly modified form of 80 my invention adapted to a similar clutch mechanism for watches.

Referring to the drawings in which similar reference characters designate corresponding parts throughout the several views, the following is a brief outline of the 85 operation of my invention, and will be clear to those familiar with the art of horology.

In the form of watch shown in Figure 1, and which illustrates certain of the parts of the setting and winding mechanism, particularly of the Hamilton and Illinois watches, but which may also be adapted to other forms of watches, the winding pinion is indicated at 50 and the winding stem or arbor which is adapted to rotate to wind 90 and set the watch movement being shown at 52, this stem as is usual being vertically movable by a push or pull upon the crown, (not shown) and which is secured upon the upper end of the stem. On the winding 100 stem or arbor is mounted the clutch 54 adapted to move vertically and to also rotate therewith, said clutch being provided with the annular groove 56. Fulcrumed at 59 is the winding and setting lever 60, the 105 lower end of which lies in the path of the stem 52.

Secured to the lever 60, preferably ad-

5 jacent is fulcrum, by means of a small bracket 62 is a depending stout leaf or bar spring 64 the lower or free end 65 of which is adapted to be moved or swung into the path of movement of a projection 22' on the seconds wheel 14. The upper end of the spring 64 is bent inwardly at 66 to provide a finger or yoke which lies within the annular groove 56. Therefore, actuation of the 10 stem 52, through lever 60 results not only in the actuation of the spring 64, but also a shifting of the clutch 54.

15 In the construction shown in Figure 3, which is that of the Waltham watch, the arrangement of the stem 52, pinion 50, and clutch 54 are substantially the same as in Figure 1, but the bar spring 76 is rigidly secured to the lever arms 72 and 74. In this form, however, the lever 68 is formed 20 in a single piece, and fulcrumed at 70. The lever is provided with two arms 72 and 74, which respectively lie within the annular groove 56 of the clutch sleeve and underlie the lower end of the stem 52.

25 Secured to the arm 72, by soldering or by suitable means, is a stout bar spring 76, the lower end of which is movable, through actuation of the lever 68, into the path of movement of the projection 22' on the seconds wheel 14.

30 In each of the forms shown in Figures 1 and 3 an outward movement of the stem to set the watch, results in a movement of the bar spring such that its lower end is moved 35 into the path of travel of the projection on the seconds wheel to cause the latter to stop at a predetermined moment.

35 In the drawings and description, I have referred particularly to certain well known 40 makes of watches, but my invention is of such a nature that same may be readily applied to use on any standard make of watch. Thus my invention may be manufactured 45 and sold as an attachment for a watch as well as a composite part thereof.

50 From the foregoing description of the construction of my improved device, it will be seen that I have provided a simple, inexpensive, and efficient means for carrying out 55 the objects of the invention, and while I have particularly described the elements best adapted to perform the functions set forth, it is obvious that various changes in form, proportion, and in the minor details of construction may be resorted to, without departing from the spirit or sacrificing any of the principles of the invention.

55 Having thus described a preferred embodiment of my invention, what I claim as 60 new and desire to protect by Letters Patent is:—

65 1. In a watch, in combination with the movement, the winding stem having thereon a shiftable clutch member provided with a recess, a seconds hand wheel, a stop device

comprising a bar having a portion disposed within the recess in said clutch member, the lower portion of said bar being arranged in proximity to said seconds hand wheel and being adapted to be moved by said clutch member into and out of engagement with said seconds-hand wheel. 70

2. In a watch, in combination with the watch movement, the winding stem having thereon a grooved clutch member, the winding and setting lever and a seconds-hand wheel a bar spring carried by said lever and provided with a yoke engaging within the groove of said clutch member, said bar spring being adapted to be moved by the operation of said winding stem into engagement with said seconds-hand wheel to stop the movement thereof. 75

3. In a watch having the usual movement and a seconds-hand wheel, a winding stem, a clutch member on said stem provided with a recess, a lever pivotally mounted within said watch, a stop device comprising a spring bar having a portion disposed within the recess of said clutch member and having its lower end disposed in proximity to said seconds-hand wheel, a guide on said lever through which said bar loosely passes, said bar being adapted to be moved through the actuation of said clutch member to cause its lower end to be brought into or out of engagement with said seconds-hand wheel to stop or release the latter. 80

4. In a watch, in combination with the watch movement, and its case, the winding stem having thereon an annularly grooved clutch member, and a seconds-hand wheel, a stop device comprising a bar spring, means for supporting said bar spring, within the watch movement case, a yoke on the upper end of said spring disposed within the groove of said clutch member, the lower end of said spring being disposed in proximity to the said seconds-hand wheel and being adapted through the movements of said clutch member to be moved into or out of engagement with said seconds-hand wheel. 100

5. In a watch, in combination with the watch movement, the winding stem having thereon a grooved clutch member, the winding and setting lever and a seconds-hand wheel, a bracket on said lever, a bar spring passing through said bracket, a yoke on the upper end of said spring disposed within the groove of said clutch member, the lower end of said spring being disposed in proximity to said seconds-hand wheel and adapted to be moved through the operation of said clutch member into and out of engagement therewith. 115

6. In a watch, including a movement having a reciprocating clutch, a seconds hand wheel, and means actuated by said clutch to arrest the movement of said seconds hand wheel. 120

7. In a watch, including a movement having a reciprocating clutch, a seconds hand wheel, and means engaged with and actuated by said clutch to arrest the movement 5 of said seconds hand wheel.

8. In a watch, including a movement having a reciprocating clutch, a seconds hand wheel, and a stop member connected with and actuated by said clutch to arrest the 10 movement of said seconds hand wheel.

9. In a watch, including a movement having a reciprocating clutch, a seconds hand wheel, means for actuating said clutch, and means actuated by said clutch for arresting 15 the movement of said seconds hand wheel.

10. In a watch, including a movement having a reciprocating clutch, a seconds

hand wheel, a stop device comprising a bar engaged with and actuated by said clutch for arresting the movement of said seconds 20 hand wheel, and means for actuating said clutch.

11. In a watch, including a movement having a reciprocating clutch, a seconds hand wheel, a bar spring having one end 25 thereof engaged with said clutch, the opposite end of said spring being adapted for engagement with said seconds hand wheel to arrest the movement thereof upon movement of said clutch in one position, and 30 means for actuating said clutch.

In testimony whereof I affix my signature.

ABRAHAM BURNSTINE.
